UNITED STATES PATENT OFFICE.

FREDERICK M. GODDARD, OF BROOKLYN, NEW YORK, ASSIGNOR TO WESTERN ELECTRIC COMPANY, INCORPORATED, OF NEW YORK, N. Y., A CORPORATION OF NEW YORK.

ELECTRICAL RESISTANCE ELEMENT.

1,856,617.

Specification of Letters Patent. Patented Oct. 26, 1920.

Application filed March 12, 1920. Serial No. 365,268.

To all whom it may concern:

Be it known that I, FREDERICK M. GODDARD, a citizen of the United States, residing at Brooklyn, in the county of Kings, State of New York, have invented certain new and useful Improvements in Electrical Resistance Elements, of which the following is a full, clear, concise, and exact description.

This invention relates generally to electrical resistance elements and more particularly to mountings for resistance elements.

The object of the invention is to provide a mounting for a resistance element of the crystal type which shall maintain under all conditions a perfect contact between the elements thereof.

A further object of the invention is to provide a mounting for a crystal such that the crystal may be used as a bilateral conductor of variable resistance.

Crystals such as carborundum have the property of varying in electrical resistance to a degree greatly out of proportion to the voltage applied. Experiments show, for example, that with a change of voltage from one to twenty-one volts, the resistance changes from 6660 ohms to 50 ohms. Professor G. W. Pierce in his text book entitled "Principles of Wireless Telegraphy," published in 1910, describes, on pages 168 and 169, experiments showing the action of a carborundum crystal when making relatively good conducting contact with two electrodes.

The results show that under such conditions the crystal is a bilateral conductor, the resistances being approximately equal in both directions.

This invention is particularly useful in systems such as that described in Roy D. Conway application Serial No. 224,975, filed March 27, 1918. It is also useful when connected in shunt with a telephone receiver to shunt comparatively large currents due to ringing currents, switching and the like. So used it is practically opaque to voice currents and insures the listener against loud receiver clicks, ringing in the receiver, and the like.

In accordance with the invention in its preferred form good electrical contact is made with the carborundum or other suitable crystal by embedding one end of the crystal in a mass of fusible metal and immersing the other end in a mercury bath.

Insulating material prevents the fusible metal from contacting with the mercury. The mercury and the fusible metal form the two electrodes for connection in a circuit.

The invention in its preferred embodiment, is shown in the drawing in which portions are cut away to show the internal structure.

A carborundum crystal 1 is held in a cup 3 of brass or other conductive material by means of a mass of fusible metal 2. The fusible metal used for the purpose is preferably type metal which on cooling expands to grip the crystal firmly. The cup 3 is provided with a cylindrical projection 4.

A glass container 5 fits over the cup 3. A washer 13 of insulating material fits about the projection and extends beyond the cup 3 so as to support both the cup 3 and the container 5. The cup 3 is held firmly in the container 5 by means of an insulating cement 6 inserted into the container 5 through the aperture 8. The cement 6 serves not only to hold the cup 3 but to cover the surface thereof and of the fusible metal 2. A portion of the crystal 1 is left exposed and protruding above the cement layer. The remaining space within the container 5 is almost entirely filled with a liquid 7. Mercury, being a good electrical conductor, chemically stable and not volatile, is preferred for this purpose. The space 14 is left to allow the mercury to expand with the temperature without bursting the container 5.

A cylindrical casing 10 made of conductive material preferably brass, is provided with a thread 12, somewhat like that of an incandescent lamp base. The lower end 15 is turned in so that when the vessel 5 is placed in the casing 10 the washer 13 fits snugly against it.

One leg of the L shaped iron rod 9 projects through the aperture 8 in the vessel 5 and dips into the mercury bath 7. The other leg of the rod 9 extends through the aperture 16 and is soldered to the casing 10.

The space between the vessel 5 and the casing 10 is filled with a cement 11 which also seals the aperture 8 and holds the structure solidly together.

A mounting is thus provided in which there is a minimum danger of breakage, and

which is unaffected by vibration or the position in which it is mounted.

What is claimed is:

1. A variable resistance element comprising conducting crystal, a metallic supporting member for said crystal, a mercury bath for said crystal making relatively good contact therewith, and insulating means separating said supporting member from said mercury bath.

2. A variable resistance element comprising conducting crystal, a metallic supporting member for said crystal, a mercury bath making relatively good contact with said crystal, insulating means separating said mercury bath from said supporting member, a container for inclosing said mercury bath and said supporting member, means for hermetically sealing the said cup within the said container, external terminals, and conductor means connecting said mercury bath and said cup respectively with said external terminals.

3. A bilateral variable resistance element comprising an active crystal, a metallic supporting cup for said crystal, fusible metal means for supporting said crystal in said cup, a mercury bath making relatively good contact with said crystal, insulating means separating said mercury bath from said cup and said fusible metal means, a container for inclosing said mercury bath and said cup, means for hermetically sealing the said cup within the said container, external terminals, and conductor means connecting said mercury bath and said cup respectively with said external terminals.

4. A bilateral variable resistance element comprising a casing of conductive material, a screw thread pressed therein, a container inclosed in said casing, said container being open at the bottom and provided with an aperture at the top, a cup within said container, said cup being of conductive material and provided with a projecting portion protruding through said casing, an active crystal, fusible metal means for supporting said crystal, a layer of insulating cement covering said cup and said fusible metal means and sealing said cup within said container, a conducting rod projecting through the aperture in the container and

fastened to said casing, a mass of liquid substantially filling the remaining space within said container, and a composition sealing said container within said casing.

5. A bilateral variable resistance element comprising a cup, an active crystal supported by the cup, a liquid bath in which a portion of the crystal is submersed, a container in which the liquid bath and the said cup are contained, a casing inclosing the container, a composition for sealing the said container within the said casing, terminal means for connecting the resistance element in a circuit and conductor means for connecting said mercury bath and said cup, respectively, with said terminal means.

6. A bilateral variable resistance element, comprising a supporting member, an active crystal supported by the supporting member, a mercury bath submersing a portion of the said crystal, a container in which the mercury bath and said supporting member are contained, a casing inclosing the container, a composition for sealing the said container within the said casing, terminal means for connecting the resistance element in a circuit, and conductor means for connecting said mercury bath and said supporting member, respectively, with said terminal means.

7. A bilateral variable resistance element comprising a supporting member, an active crystal supported by the supporting member, a mercury bath submersing a substantial portion of the said crystal, a container in which the mercury bath and said supporting member are contained, an insulating composition for separating the said mercury bath from the said supporting member, and for sealing the supporting member within said container, a casing inclosing the container, a composition for hermetically sealing the container within the casing, external terminal means for connecting the resistance element in a circuit, and conductor means connecting said mercury bath and said supporting member, respectively, to said terminal means.

In witness whereof, I hereunto subscribe my name this 10th day of March A. D. 1920.

FREDERICK M. GODDARD.
